UNITED STATES PATENT OFFICE.

LEOPOLD HESSE, OF OBERBRUCH, NEAR AACHEN, GERMANY, ASSIGNOR TO
VEREINIGTE GLANZSTOFF-FABRIKEN A. G., OF ELBERFELD, GERMANY.

PROCESS FOR MANUFACTURING TUBULAR PRODUCTS OF CELLULOSE OR COMPOUNDS OF CELLULOSE.

1,341,745.

Specification of Letters Patent. Patented June 1, 1920.

Application filed June 21, 1916, Serial No. 105,058. Renewed February 5, 1920. Serial No. 356,419.

To all whom it may concern:

Be it known that I, LEOPOLD HESSE, a subject of the German Empire, residing at Oberbruch, near the city of Aachen, Kingdom of Prussia, Empire of Germany, have invented a certain new and useful Process for Manufacturing Tubular Products of Cellulose or Compounds of Cellulose; and I do hereby declare the following to be a full, clear, and exact description of my invention.

My invention relates to a process of manufacturing tubular products of cellulose or cellulose compounds as substitute for straw and similar products. The production of which from solutions of cellulose has not been successful till now.

Attempts were made to produce such imitations by injecting solutions of cellulose through slit-shaped openings of different forms, but only ribbon-like products were obtained without the desired properties.

My invention consists in injecting solutions of cellulose of any kind through slit-shaped openings into a reciprocating bath and rolling up the resulting more or less coagulated ribbon-like products into endless spirals of tubular form in a spinning process. The product shows the optical effect of layers of thin transparent lamellas pressed together. This effect varies with the thickness and form of the ribbons, the relative position of them, and the tension in the spirals.

The thickness of the ribbons depends upon the width of the slits, the constitution of the cellulose-solution and the stretching during the spinning process, the latter and the properties of the precipitating bath being essential for the tension in the dry material. The slits may be of any suitable form, they may be straight, curved or indented. The ribbons may also be twisted several together.

For spinning I use a so-called spinning pot or a spinning centrifuge. By varying the sort of solution of cellulose, by using slits of different width and shape, by changing the quality of the precipitating bath and the manner of spinning, influencing the shrinkage and tension in the finished fabric, I can produce fabrics of different appearance, which are to be used as substitutes for straw, hemp, tagal-fiber, etc., having the advantage of being endless.

The process resembles the method for producing jute, in which paper, cut to strips, is 55 rolled up in spirals and twisted to tubular products. The paper strips may also be replaced by finished strips of cellulose films which may be rolled up in endless spirals, but the obtainable fabrics are far inferior to 60 the products which I obtain by my wet spinning process in a more economical way.

For finishing the fabrics I treat them in the same way as the fabrics of artificial silk, by washing out the precipitating chemicals 65 and drying under tension.

The feature of my invention is the production of fabrics of great softness, with separated heat isolating spaces in the interior of the product.

An apparatus which may be used in producing the tubular threads is illustrated in the accompanying drawing, wherein Figure 1 is a somewhat diagrammatic view of the apparatus, and Fig. 2 is a view of the "spinning" nozzle and showing the character of the projected and spirally twisted filament. In said drawings, A designates a "spinning" nozzle having a long narrow slit a therein from which the cellulose solution 75 is projected in a broad thin strip or ribbon and precipitated in the bath B. Preferably the precipitated strip of cellulose, while still plastic, is led over a roll c to a rotating spinning pot C having feed rolls c', the cellulose 80 strip being wound into hollow spiral form 85 between the roll c and rolls c', and coiled in the bottom of the pot C. A rack and gear c² c³ turns the feed rolls c'.

What I claim is:

A process for manufacturing tubular cords of cellulose or cellulose-compounds, consisting in injecting solutions of cellulose or cellulose compounds through elongated spinning slits into precipitating baths and 95 rolling up the resulting ribbons or strips into endless spirals by spinning or twisting, substantially as set forth.

In testimony that I claim the foregoing as my invention, I have signed my name in 100 presence of two subscribing witnesses.

LEOPOLD HESSE.

Witnesses:

HENRY C. A. DAMM,
HENRY CUADFLIEG.
